UNITED STATES PATENT OFFICE.

ALBENUS B. WISEMAN, OF GRAND RAPIDS, MICHIGAN.

ELECTRICAL CONNECTER.

Application filed September 12, 1925. Serial No. 56,011.

This invention relates to improvements in electrical connectors and while designed primarily for use in connection with portable electric motors, may be employed in making 5 electrical connections between a source of current supply and various other electrical machines or apparatuses.

One of the objects of the present invention is to provide a connector embodying a 10 socket and a plug insertable therein and in which the socket will be so constructed that all contacts therein will be completely covered when the plug is not in place, so that a workman will not be liable to be injured by 15 coming in contact with any live wires or contacts when inserting or removing the plug or even if, through ignorance, he should insert his fingers into the socket. Likewise, the invention contemplates a connector embodying 20 a socket so constructed that the insertion of a tool or any other metallic object into the plug will not cause disasterous results.

Another object of the invention is to so 25 construct the connector that when the plug is properly inserted it can not be directly pulled out of the socket or otherwise displaced to cause short circuiting or imperfect contact of the coating conductor terminals of the plug and socket.

30 Another object of the invention is to provide a connector so constructed that, when the plug is either inserted or not inserted, the conductor contacts within the plug will be protected by an insulating medium in such 35 a manner as to prevent injury thereto or water coming in contact therewith.

Another object of the invention is to so construct the connector that the conductor terminals of the plug and socket will be securely held in mutual engagement when the plug is properly inserted into the socket, so that there can be no imperfect contacts between the parts which might result in damaging the motor or other machine or apparatus to be supplied with current.

In the accompanying drawings:

Figure 1 is a vertical sectional view through an electrical connector embodying the invention.

Figure 2 is a vertical front to rear sectional view through the socket of the connector, the plug being removed.

Figure 3 is a horizontal sectional view taken substantially on the line 3-3 of Figure 2, looking in the direction indicated by the arrows.

Figure 4 is a perspective view illustrating a set of the plug and socket conductor terminals in position about to be engaged.

Figure 5 is a top plan view of the plug, 60 one of the conductor terminals of the plug being shown in section.

Figure 6 is a diametric sectional view taken substantially on the line 6-6 of Figure 5, looking in the direction indicated by 65 the arrows.

Figure 7 is a perspective view of the insulating member of the socket.

Figure 8 is a sectional view illustrating a 70 modification in the construction of the conductor terminals of the socket.

In the illustrated embodiment of the invention, the connector is designed for use in connection with motors of the three-phase type with ground connection, two-phase type 75 without ground connection, or single-phase type with ground connection, and the socket of the connector is designed for attachment to any suitable fixed support such as a wall. The said socket comprises a cylindrical metallic body shell indicated by the numeral 1 and provided interiorly at its open lower end with an annular flange 2 and, exteriorly, at its open upper end, with an outstanding annular flange 3. A cap section 4 is provided to close the upper end of the body shell 1 and is of dome-like form, the cap section being provided interiorly at its open bottom with an inwardly projecting annular flange 5 into which are threaded bolts 6 90 which are engaged through openings in the flange 3 of the body shell 1, to secure the parts together, a packing gasket 7 being interposed between the flanges 3 and 5 so as to insure against the entrance of moisture 95 between the flanges. The cap section 4 is provided at its rear side with an attaching portion 8 having openings 9 through which any suitable securing elements such as screws or bolts may be engaged for the purpose of 100 securing the cap section to a fixed support, and thereby support the socket as a whole, and in advance of the said attaching portion and in its upper side, the cap section 4 is formed with a threaded opening 10 into 105 which may be fitted a conduit (not shown) for the conductor wires which lead into the socket and are indicated by the numeral 11.

Arranged within the body shell 1 of the plug is a body 12 of insulating material, 110 preferably porcelain, and in order to accommodate the plug which will presently be

described, the said body is formed axially with a cylindrical bore indicated by the numeral 13, the bore opening through the upper and lower ends of the said body 12 and the said body being supported at its bottom upon the flange 2, as best shown in Figures 1 and 2 of the drawings. An annular flat gasket 14 of insulating material is disposed upon the upper end of the body 12, and an annular metal plate 15 is disposed upon the upper side of the gasket 14, bolts 16 being fitted through the flange 2, the body 12, gasket 14, and plate 15, and nuts 17 being threaded upon the upper ends of the bolts to bear against the upper side of the said plate 15 and thus secure the parts in their assembled relation.

A series of recesses 18 is formed in the wall of the bore 13 of the body 12 and open at their upper ends through the upper end of the body and at their lower ends terminate approximately midway between the upper and lower ends of the body, the bottom walls of the said recesses being indicated by the numeral 19. Grooves 20 are likewise formed in the wall of the bore 13 and extend vertically and open at their lower ends through the bottom of the body 12 and at their upper ends through the top of the said body, the grooves being located at one side of a respective one of the recesses 18, so that the recesses have open sides presented to their respective grooves.

Arranged within each of the recesses 18 is a conductor terminal or contact indicated in general by the numeral 21 and most clearly shown in Figure 4 of the drawings. This contact comprises a base portion 22 which is of metal and which has an integral upstanding contact finger 23 the upper end of which is rounded as at 24, for a purpose which will presently be made apparent. The contact finger 23 being integral with the base 22, is, of course, fixed, and the contact as a whole comprises a second contact finger which is indicated by the numeral 25 and of substantially the same contour as the finger 23, being provided with a rounded end 26. This contact finger 25 is yieldably supported in a manner which will now be explained. A thin copper leaf 27 and a steel spring leaf 28 are disposed in overlapping relation and are secured at their lower ends, by screws 29, to that end of the base 22 opposite the end which supports the finger 23. Screws 30 are secured through the leaves 27 and 28 and threaded into the outer side of the finger 25, and the leaves are formed with a slight bend, as indicated at 31, near their lower ends and immediately above the upper surface of the base 22, so that the finger 25 is yieldably supported in a position inclining toward the finger 23, the rounded upper ends of the fixed and yieldable fingers being located opposite each other and in spaced re-

lation. Screws 32 are threaded through the body 12 of the socket and are threaded into openings 33 formed in the bases 22 of the several contacts, and it will be observed that in this manner the contacts are secured in place with their bases 22 resting upon the bottom walls 19 of the respective recesses. The screws 32 pass also through conductor strips 34 which are disposed against the inner walls of the respective recesses 18 and preferably seated flush in said walls as shown in Figure 3 of the drawings. The screws 32 pass through the lower ends of the strips 34 and the upper ends of the strips are secured by screws 35 fitted through the outer side of the body 12 and threaded into openings 36 formed in the upper end portions of the respective strips 34. Each strip 34 at its upper end is formed with incisions and bent to provide wire gripping lugs 37, and the conductor wires 11 are led through insulating bushings 38 in the plate 15, and are anchored by the lugs 37 to the respective conductor strips 34. Where three leads or conductors are present in the circuit, they are connected to three of the conductor strips 34 and where a ground is employed the conductor wire which is indicated by the numeral 39, is connected to the fourth one of the conductor strips 34, at one end and at its other end by a binding screw 40, to a boss 41 formed upon the inner side of the cap section 4 at the front thereof, as best shown in Figure 2 of the drawings, so that this particular contact is grounded by way of the casting of the socket.

It will be evident from the foregoing that inasmuch as the contacts 21 are of a width substantially equal to the width of the recesses in which they are housed, the edges 105 of the contact fingers 23 and 25 will be presented inwardly at the surface of the wall of the bore 13 in the body 12, and in order to preclude any possibility of a workman short circuiting any of the contacts by carelessly inserting tools or other metallic objects into the socket, and likewise in order to provide against injuries which would result if he inserted his fingers into the socket and the contacts were exposed, means 110 is provided for shielding the contacts when the plug is not inserted in the socket, this feature constituting also, as will be presently explained, a medium whereby the plug will be securely held in place when properly fitted into the socket. The means referred to above comprises a metallic shell 42 which is preferably of rectangular form and open at its bottom where it is provided with a flange 43 through which securing elements 125 44 are engaged to secure the shell to the upper side of the plate 15 and insulating gasket 14. The openings in the said gasket or disc 14 and the plate 15 are indicated respectively by the numerals 45 and 46, and 130

the numeral 47 indicates a cylindrical body of fiber or other suitable insulating material which is slidably fitted through the said openings 45 and 46. The body 47 is provided at its upper end with a substantially rectangular head 48 which more or less snugly fits within the shell 42, so that rotation of the body 47 is prevented and yet the body may have free up and down movement through the openings 45 and 46. The openings 45 and 46 are of the same diameter as the bore 13 of the body 12 and it will be observed by reference to Figure 2 of the drawings, that normally the body 47 occupies a position filling the upper end of the bore and completely covering the inwardly presented edges of the fingers of the contacts 21. A tubular guide 49 is secured to the under side of the closed top 50 of the shell 42, centrally thereof, and extends downwardly within the shell and projects at its lower end within the upper end of a bore 51 which is formed axially in the body of the insulator or shield 47. A compression spring 52 is arranged within the tubular guide 49 and bore 51 and at one end fits over a boss 53 at the upper end of the guide and at its lower end fits over a similar boss 54 secured in place by a pin 55 which extends through the lower end of the body 47 of the insulating shield and which pin is provided with a head 56 constituting an abutment and wear element. By reference to Figure 2, it will be observed that the spring normally holds the member 47 in the lowered position in which it fills the upper end of the bore 13 and covers and protects the contacts 21, and it will further be observed by reference to this figure that in this position of the member, the head 48 rests at its under side upon the upper side of the plate 15 adjacent the opening 46 therein, so that by reason of this mutual engagement of the parts, the downward movement of the member 47 is limited.

The plug of the connector is indicated in general by the numeral 57 and the same comprises a one piece body portion 58 and handle 61 cylindrical in form and of some suitable insulating material such for example as hard maple wood. The body is formed with an axial bore 59 which at one end communicates with a bore 60 formed in the handle 61. A circular guard 62 is provided at the juncture of the body 58 and the handle 61 and may be of rubber or other insulating material so as to protect the hand of the user when inserting the plug into the socket. The bore 59 of the plug body 58 terminates short of the opposite end of the body or, in other words, the end which is to be introduced into the bore 13 of the socket, and a series of slots 63 are formed in the said body 58 near its said end and communicate with the bore 59, the

slots corresponding, of course, in number to the number of contacts which are to be carried by the plug body. These contacts are indicated in general by the numeral 64 and each comprises a metal body having a head 70 portion 65 provided with a depending nose 66, the lower side of which is transversely rounded as at 67, so as to adapt the same to readily enter between the rounded upper ends 24 and 26 of the contact fingers 23 and 25 of the respective contacts 21 when the plug is fitted into the socket. The head 65 of each of the contacts 64 is formed with an opening 68, and a screw 69 is fitted through the opening and threaded into a bushing 70 embedded in the plug body 58. Conductor strips 71 are disposed flush in the surface of the body 58 above the upper ends of the slots 63 and between the body and the inner sides of the respective contacts 64, 85 the rounded lower side 67 of each contact being located immediately at the upper end of a respective one of the said slots. Each conductor strip 71 is turned inwardly at right angles as at 72, against the top wall 90 of the respective slot 63, and thence downwardly at right angles, as at 73, against the upper portion of the inner wall of the respective slot, and securing screws 74 are fitted through these latter portions of the conductor strips and are threaded into bushing 75 embedded in the insulator plug body 58. A cable 76 is led from the motor or other electrical apparatus or machine to be supplied with current, through the bore 60 100 of the handle 1, which handle is preferably treated with a suitable water-proofing composition, and the wires constituting a part of this cable and indicated by the numeral 77, are led through respective ones of the conductor strips 71 and connected by binding screws 78 to the projecting lower end portions 73 of said strips. An abutment and wear element 79 is preferably secured to the end of the plug body 58 to contact the corresponding element 56 of the socket. 110

By comparison of Figures 3 and 5 of the drawings, it will be observed that the grooves 20 and the contacts 64 are of such dimensions that the contacts may enter the lower ends of the grooves, at the time the plug is inserted into the socket, and pass upwardly through the grooves to coact with the respective contacts 21 when the plug has been rotated to the right 115 a short distance, approximately one-eighth of a revolution, and the spring 52 has expanded to force the plug in an outward direction, or the handle 61 is manually pulled outwardly, it being understood that at the time of insertion of the plug into the socket, the insulating shield 47 will be forced inwardly against the tension of the spring 52. It will now be evident, by reference to Figure 2 of the drawings, that when 120 125 130

the plug is not inserted in the socket, the insulating body 47 will completely cover and protect the contacts 21 so that a workman cannot suffer injury through contact of his fingers with any of the contacts or with any other current carrying portion or element of the socket. It will likewise be evident that the body 47, by covering the contacts and substantially filling the bore 13, when said body is in the projected position shown in the said Figure 2, effectually prevents the entrance of moisture into the socket to corrode the contacts. Likewise, no short circuiting can occur if a careless workman should insert a tool or other metallic object into the socket. Likewise, as the plug is fitted into the socket, the plug body will occupy the space formerly occupied by the lower portion of the insulating body 47, so that the contacts of both the socket and plug are protected as in the former instance. It will also be evident from the foregoing that the pressure exerted by the insulating body 47 through the medium of the spring 52, against the plug body 58, when the contacts of the plug are in engagement with the contacts of the socket, insures against any accidental disarrangement of the parts and likewise insures against the plug being accidentally pulled out of the socket if any strain is imposed upon the cable 76, inasmuch as to disengage the plug from the socket, it is necessary to shove the plug inwardly and then rotate the same to bring the plug contacts into alignment with the respective slots 13. By reference to Figures 3 and 5 of the drawings, it will also be observed that one of the grooves shown in Figure 3 is of less width than the other grooves, and likewise one of the contacts shown in Figure 5, is of less thickness than the other contacts, and therefore, it is impossible for the plug to be inserted into the socket except in the proper and intended manner. It will, furthermore, be evident that inasmuch as the contacts of the plug are held firmly in engagement with the contacts within the socket, through the pressure exerted by the spring 52 against the insulating body 47, and likewise due to the frictional engagement of the noses 66 of the contacts 64 between the fixed and yieldably supported fingers of the contacts 21, there can be no play between the contacting parts such as would be liable to cause arcing or short circuiting.

Figure 8 of the drawings illustrates a modified form of socket contact and in this figure, the numeral 80 indicates in general the contact which is mounted in the same manner as the contact shown in Figure 4 of the drawings and includes a base portion 81 corresponding to the base portion 22 of the previously described contact, and a fixed contact finger 82 extending upwardly there-

from. In this embodiment, the yieldable contact finger is indicated by the numeral 83 and the same is supported by spring leaves 84 corresponding to the leaves 27 and 28, at that end of the base portion 81 opposite the 70 end from which the contact 82 extends. In this embodiment, however, a screw 85 is threaded at one end into the yieldable finger 83 and extends loosely through a slot 86 formed in the fixed contact finger 82, a 75 spring 87 being arranged upon the said screw to bear between the head 88 thereof and the outer side of the finger 82, so as to yieldably draw the finger 83 toward the finger 82. 80

Having thus described the invention, what I claim is:

1. An electrical connector comprising a socket, and a plug, the socket including a body of insulating material having a bore to receive the plug, said bore having open sided recesses in its wall, a plurality of contacts supported by the body and arranged within the recesses, a plurality of contacts upon the plug for engagement with the first mentioned contacts when the plug is inserted into the bore, and an insulator movable within the bore and normally occupying a position for closing the open sides of the recesses for shielding the first mentioned contacts and displaceable by the plug upon its insertion into the bore, said plug and insulator having intimate sliding engagement with the wall of the bore. 90

2. An electric connector comprising a 100 socket, and a plug, the socket including a body of insulating material having a bore to receive the plug, said bore having open sided recesses in its wall, contacts supported by the body and arranged in the recesses, a plurality of contacts upon the plug for engagement with the first mentioned contacts when the plug is inserted into the bore, an insulator movable within the bore and normally occupying a position for closing the open 105 sides of the recesses for shielding the first mentioned contacts and displaceable by the plug upon its insertion into the bore, said plug and insulator having intimate sliding engagement with the wall of the bore, and 110 means yieldably holding the insulator in its said normal position. 115

3. An electrical connector comprising a socket, and a plug, the socket including a body of insulating material having a bore to receive the plug, the said bore being cylindrical and having grooves and recesses formed in its walls, a plurality of contacts supported by the body and arranged about the wall of the bore in said recesses and relatively displaced with relation to the upper end of a respective one of the grooves, a plurality of contacts upon the plug engageable through the grooves at the time of insertion of the plug into the bore and en- 120 125 130

gageable with respective ones of the contacts first mentioned, when the plug is rotated after insertion, and an insulator slideable within the socket and yieldably exerting pressure against the plug to maintain the same in position with the contacts thereon engaging the first mentioned contacts, said insulator also serving to shield the first mentioned contacts when the plug is withdrawn from the bore of the body.

4. An electrical connector comprising a socket, and a plug, the socket including a body of insulating material having a bore to receive the plug, the said bore being cylindrical and having grooves and recesses formed in its walls, contacts mounted in the recesses and relatively displayed with rela-

tion to the upper ends of respective grooves, a plurality of contacts upon the plug engageable through the grooves at the time of insertion of the plug into the bore and engageable with respective ones of the first mentioned contacts, when the plug is rotated after insertion, a cylindrical body of insulating material movable longitudinally within the bore and having intimate sliding engagement with the wall of the bore, and a spring coacting with the said body and yieldably normally holding the same in position to close the recesses shielding the first mentioned contacts.

In testimony whereof I affix my signature.

ALBENUS B. WISEMAN. [i. s.]
